UNITED STATES PATENT OFFICE.

MARTIN V. HAMMACK, OF SPRINGFIELD, MISSOURI.

TROUSERS APPLIANCE OR DEVICE.

1,049,578.

Specification of Letters Patent.

Patented Jan. 7, 1913.

Application filed February 20, 1912. Serial No. 678,966.

To all whom it may concern:

Be it known that I, MARTIN V. HAMMACK, a citizen of the United States, residing at Springfield, in the county of Greene and 5 State of Missouri, have invented certain new and useful Improvements in Trouser Appliances or Devices, of which the following is a specification.

My invention relates to improvements in 10 trousers appliances or devices, and refers particularly to a device which will perform the functions of pressing, creasing and stretching trousers.

One object of the invention is the provision of a device of the character stated which can be instantly applied and adjusted to any size or shape of trousers, and which will perform the creasing and stretching 15 of the trousers, and insure a perfect shape 20 and condition to the trousers.

Another object of my invention is the provision of a trousers device which will be light in weight and which can be collapsed or folded to permit of its being carried in a 25 trunk or suit case, as occasion demands.

Another object of my invention is the provision of a trousers device which will occupy a small amount of space; which can be applied instantly and adjusted to the trousers; 30 which can be produced at the right price and which will prove efficient and practical in every particular.

To attain the desired objects, my invention 35 consists of a trousers device or appliance embodying novel features of construction and combination of parts, substantially as disclosed herein.

In order that the detailed construction 40 and the operation of my appliance may be readily understood and its advantages be fully appreciated, I have illustrated in the accompanying drawings an embodiment of my invention, it being understood that I may make such changes and additions as 45 fall within the scope of my invention.

Figure 1 is a side view of the device applied to the trousers leg, the trousers being shown in section. Fig. 2 is a side view, on an enlarged scale, showing the adjusting 50 mechanism and upper part of my device. Fig. 3 is a detail view of the lower part of the device. Fig. 4 is a sectional view of the joint connecting the sections of the device.

Fig. 5 is a sectional view of the adjusting 55 mechanism. Figs. 6, 7 and 8 are enlarged

detail views of the parts of the improvement.

In the drawings:—The letter A designates the main part or support of my device, which preferably consists of a tubular rod 60 formed of a series of sections B, connected by a male and female threaded plain or socket connection C, which permits of the collapsing of the support to enable the device to occupy a small space. 65

To the lower end of the support is pivoted at D, the cross-piece E, to which is connected the plate F, which is of tapered or curved shape to permit the ready insertion in the trousers leg, and to the upper end of 70 the tubular support is secured the flat cross-piece G, of greater width than the cross-piece E.

To the lower cross-piece E is fitted the pair of flat sleeves E', having wire receiving 75 recesses E², and to the upper cross-piece G, is fitted a pair of flat sleeves G', having wire receiving recesses G², and the sleeves G' are formed with flaps H, which are connected with the pair of pivoted arms J, formed 80 with racks J', and the arms lead to the ears K, on the tube K' above the cross-piece G, said tube guiding the adjusting rod L, which has the operating crank or handle M, and its threaded portion N engaging the 85 threaded thimble O in the support.

From this construction, it will be observed that the appliance is placed in the trousers, and that the flat sleeves are adjusted laterally to fit the upper and lower portions of the trousers, and when adjusted, the turning of the rod and screw moves the pair of racks J' and brings the pair of wires P, which fit in the recesses of the lower sleeves at P', and engage the upper recesses 90 of the sleeves at P², and are formed with loops Q, retained in proper place by sliding sleeves Q', which engage any of the teeth of the racks J', forcing the wires P into 95 engagement with the legs of the trousers, the wires being drawn taut and fitting the inside of the trousers to effect a pressing, creasing and stretching of the trousers. 100

It is evident that the device will give the proper crease to the trousers from the hip or seat to the end of the leg and save the annoyance and expense consequent upon pressing with a hot-iron. 105

It will also be seen that the device may be adjusted to any size or shape of trousers 110

and will perform its functions in a practical and efficient manner and that by reason of its simplicity, durability and cheapness will insure a useful and desirable article for the purpose designed.

I claim:—

1. A device of the character described, consisting of a support, a pair of cross-pieces arranged horizontally with reference to the support connected to said support, a plate connected to one of said cross-pieces and shaped to permit ready insertion into the trousers leg, and laterally adjustable means mounted on the cross-pieces for engaging the seat and leg of the trousers.
2. A device of the character described, consisting of a support, a pair of cross-pieces arranged horizontally with reference to the support connected to said support, a plate connected to one of said cross-pieces and shaped to permit ready insertion into the trousers leg, laterally adjustable means mounted on the cross-pieces for engaging the seat and leg of the trousers, and connections between the cross-pieces to bear against the trousers to effect the creasing and pressing.
3. A device of the character described, consisting of a tubular support, a pair of cross-pieces mounted on the support, a pair of rack bars having their lower ends connected to the upper cross-piece, a rod having a handle and adjustable in the tubular support, and a pair of wires having a loop at one end to engage the rack bars and having their other ends connected to the lower cross-piece.
4. A device of the character described, consisting of a support, an upper and lower cross-piece carried by the support, a pair of

laterally adjustable sleeves carried by the cross-pieces to fit the seat and leg and wires connecting the sleeves and engaging the trousers to effect the creasing and stretching.

5. A device of the character described, consisting of a support, a pair of cross-pieces mounted upon the support, an adjusting rod mounted in the support, a pair of rack bars adjusted by the rod, and a pair of wires having their lower ends connected to the lower cross-piece and their upper ends engaging the rack bars.

6. In a device of the character described, the combination of a support, an upper wide cross-piece and a lower narrower cross-piece mounted upon the support, lateral adjusting sleeves fitted on the cross-pieces and having recesses in their edges, a pair of wires fitting and carried in said recesses, a pair of rack bars engaged by the upper ends of the wires, and an adjusting device operating to tighten said wires.

7. In a trousers appliance, the combination with a support having cross-pieces connected thereto, of an operating rod rotatably mounted in said support, devices adjustable in their angular relation to said cross-pieces and connecting the cross-pieces and operating rod, and wires connected to said devices and engaging the trousers to effect the creasing and stretching of the trousers.

In testimony whereof I affix my signature in presence of two witnesses.

MARTIN V. HAMMACK.
